US0D1005092S

(12) **United States Design Patent** (10) **Patent No.:** **US D1,005,092 S**
(45) **Date of Patent:** **** Nov. 21, 2023**

(54) **BRACKET**

(71) Applicants: **HANGZHOU UNITED TOOLS CO., LTD.**, Hangzhou (CN); **HANGZHOU GREAT STAR INDUSTRIAL CO., LTD.**, Hangzhou (CN)

(72) Inventor: **Weiyi Wang**, Hangzhou (CN)

(73) Assignees: **Hangzhou United Tools Co., Ltd.**, Hangzhou (CN); **Hangzhou Great Star Industrial Co., Ltd.**, Hangzhou (CN)

(**) Term: **15 Years**

(21) Appl. No.: **29/761,445**

(22) Filed: **Dec. 9, 2020**

(30) **Foreign Application Priority Data**

Jun. 15, 2020 (CN) 202030303883.X

(51) LOC (14) Cl. **08-05**

(52) U.S. Cl.

USPC **D8/71; D19/90**

(58) **Field of Classification Search**

USPC D8/71, 373, 380-381, 499; D19/75, 90

CPC A47B 63/00; B25H 3/00; B25H 3/028;
B25H 3/04

(57) **CLAIM**

The ornamental design for a bracket, as shown and described.

DESCRIPTION

FIG. 1 is a perspective view of a first embodiment of a bracket according to my new and ornamental design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof; and,

FIG. 7 is a bottom plan view thereof.

The portions of the bracket shown in broken lines form no part of the claim.

1 Claim, 7 Drawing Sheets
